UNITED STATES PATENT OFFICE

JOSEPH ELMER, OF CHICAGO, ILLINOIS

RADIATOR

Application filed November 10, 1928. Serial No. 318,476.

This invention relates to improvements in radiators, and more especially a steam heating radiator.

The invention is applicable to such radiators used in either the one or two pipe system.

One of the features of my invention is the provision of means for increasing the circulation in the radiator and preventing banking or trapping of air that otherwise might interfere with the efficiency of the radiator.

Another feature of my invention is the provision of improved air-venting apparatus.

Other features and advantages of my invention will appear more fully as I proceed with my specification.

In that form of the device embodying the features of my invention shown in the accompanying drawings, Fig. 1 is a vertical sectional view of a radiator as used in a one pipe system; Fig. 2 is a similar view showing a radiator as adapted for use in a two pipe system; Fig. 3 is a vertical sectional view of the air-venting apparatus; and Fig. 4 is a vertical sectional view of the obstructing disk or device forming a part of the air circulating means.

Since the radiators for the one and two pipe systems are similar in many respects, I shall describe them both at the same time and merely point out the differences.

As shown in the drawings, the radiator comprises a plurality of intermediate sections 10, 10, and two end sections A and B, connected together in any suitable manner; for example, by the close nipples 10¹. To aid in an understanding of the invention, I shall designate the end section A as the feed section, and the end section B as the vent section. In the one pipe system, the vent section B, as shown in Fig. 1, is closed at the bottom by means of the plug B¹. In the radiator shown in Fig. 2 for a two pipe system, this vent section B is provided at the bottom with a pipe outlet B¹¹.

A¹ indicates the usual valve-controlled steam inlet pipe entering the bottom of the feed section in the usual manner.

To aid in circulating the air in the radia-

tor, I provide an obstructing disk or device 11 between the feed section and the next adjoining section at the bottom. This disk or obstructing device is provided with a threaded air outlet opening 11¹, into which is threaded the short nipple 12 of an air circulating pipe. Fastened onto the nipple 12, is an elbow 13, which carries an upwardly projecting pipe 14 extending partway up into the feed section A. There is a slight difference between the two forms of obstructing device used in the radiators for the one and two pipe systems. In the one pipe system radiator, as shown in Fig. 1, the obstructing device is provided with a small second drain opening 11¹¹ below the opening 11¹. This device is shown in Fig. 4. In the two pipe system radiator, this second drain opening is omitted, as the drainage passes through outlet pipe B¹¹.

There is also provided air vent apparatus for the radiator at the upper end of the vent section B. This is shown in detail in Fig. 3. Such apparatus includes a threaded plug 20, adapted to be mounted in the screw-threaded standard upper joint opening of the section B. Such plug is provided with an opening 21 adapted to be opened or closed by a valve controlled by a temperature-responsive element. The opening 21 is provided with a valve seat at each end, the outer seat being indicated by 21^a and the inner seat by 21^b. 22 indicates a valve stem inside of the hole 21 and carrying at each end a valve head or disk substantially conical in shape. The head 22^a is adapted to seat on the seat 21^a, and the head 22^b is adapted to seat on the seat 21^b. Suitably mounted on the inside of the plug 20 by means of the screws 23, is a fluid chamber 24. 25 indicates a diaphragm in the fluid chamber provided with a central opening 26, through which extends the piston 27. 28 indicates suitable packing, and 29 a packing nut screwed into the threaded outer end of the chamber 24. 30 indicates fluid in the fluid chamber, the volume of which is responsive to changes in temperature in the vent section B. The outer end of the piston 27 normally rests against the valve head 22^b. On the outer side of the plug 20, is carried

a shell 31 in which is mounted a compression spring 32 bearing against the valve head 22^a. 33 indicates an adjusting nut to adjust the tension of the spring 32.

5 40 indicates an obstructing disk or device located in front of the vent section at the top thereof and provided with an opening 40¹.

The air-venting apparatus functions to exhaust and release the air and also keeps it out. In the operation of the device, steam 10 enters the feed section and travels upwardly in said section, as indicated by the arrows, thence through the top and thence downwardly through the other sections on top of the air, the escaping air primarily passing 15 upwardly in the vent section and out through the vent opening 21. The opening 40¹ in the disk 40 permits some steam to pass therethrough and directly engage the fluid chamber 24. Such steam, and hot air and steam, 20 passing upwardly in the vent section, serve to heat the chamber 24, causing expansion of the fluid 30 to press the piston 27 outwardly and seat the valve 22^b on the valve seat 21^b, thus preventing further escape of air. The 25 spring 32 and quantity and kind of fluid 30 are adjusted so that the valve 22^b will close when there is no longer any air to be vented. When the steam goes down or is turned off, 30 the spring 32 pushes the valve head 22^a inwardly to seat on the valve seat 21^a, preventing air from again entering the radiator.

The disk 11 with the upwardly projecting pipe 14 aids in circulating the air. Heretofore, it has been customary to take the steam in at the top of the feed section with a pipe that is run up alongside and outside of the radiator. Such a pipe detracts from the appearance of the radiator, and when steam is so taken in at the top, banking of the air frequently occurs in the feed section. These difficulties are eliminated by the use of the disk 11 and upwardly projecting pipe 14. It might be said that I use the first section 45 of the radiator, in conjunction with the disk 11 and pipe 14, as an inlet pipe to overcome banking of the air in the first section, and at the same time cause the steam to enter the intermediate sections at the tops, where 50 it will settle down on top of the cooler air and thus aid in maintaining effective circulation in the radiator.

The fluid chamber 24 of the air-venting apparatus is fastened on the inside of the plug 55 20 and is inserted through the opening in the upper end of the section B when the plug 20 is screwed into place. When finally located, such chamber 24 lies inside of the section B where it is removed from sight and danger of damage.

While I have shown and described certain 60 embodiments of my invention, it is to be understood that it is capable of many modifications. Changes, therefore, in the construction, arrangement and operation may be

made without departing from the spirit and scope of the invention disclosed in the appended claims, in which it is my intention to claim all novelty in my invention as broadly as possible, in view of the prior art. 70

What I claim as new, and desire to secure by Letters Patent is:

1. A radiator including; a plurality of sections connected together at the top and bottom and including a feed section and a 75 vent section; a temperature-responsive air vent in the top of the vent section; and an obstructing device located in front of the vent section at the top thereof, said obstructing device provided with an opening. 80

2. A radiator including; a plurality of sections connected together at the top and bottom and including a feed section; and an obstructing device in the bottom outlet of the feed section, said obstructing device being 85 provided with an air outlet opening, and an air circulating pipe connected to said opening and extending at least partway upwardly in the feed section.

3. A radiator as claimed in claim 2, in 90 which the obstructing device at the bottom of the feed section is provided with a second drain opening.

In witness whereof, I hereunto set my hand this 19th day of October, 1928.

JOSEPH ELGER.
